PULL FOR DOORS, DRAWERS AND THE LIKE

David F. James, Los Angeles, and James W. Maize, Fullerton, Calif., assignors to Hyer Hardware Mfg. Co., Anaheim, Calif., a corporation of California

Filed Mar. 2, 1966, Ser. No. 1,252

Term of patent 14 years

(Cl. D10—8)

FIG. 1.

FIG. 2.

FIG. 3.

FIG. 1 is a top plan view of a pull for doors, drawers and the like, showing my new design;

FIG. 2 is a side elevation thereof; and

FIG. 3 is a side elevation of a modified form of the pull for doors, drawers and the like showing my new design and which in top plan corresponds in appearance to the showing in FIG. 1.

The dominant features of the design reside in the portions shown in full lines.

We claim:

The ornamental design for a pull for doors, drawers and the like, as shown and described.
